UNITED STATES PATENT OFFICE.

HENRY JOSEPH SINNOTT, OF FAR ROCKAWAY, NEW YORK, ASSIGNOR TO THE COMMERCIAL CABLE COMPANY, OF NEW YORK, N. Y.

RELAY DISTRIBUTOR.

Application filed July 16, 1927. Serial No. 206,197.

My invention pertains to telegraph systems and particularly relates to high speed telegraph or cable systems in which the signals are recorded upon a tape or other medium.

Received signals which are recorded in the operation of high speed telegraph or cable circuits are usually transcribed before delivery in message form. The speed at which 10 the signals are recorded often exceeds the speed of the transcribing operator thereby confusing the operator, causing the recording tape to pile up and tangle, and resulting usually in mutilation of the tape and loss of 15 messages.

The principal object of my invention comprises providing a system of circuits and apparatus whereby signals comprising messages to be recorded may be distributed to 20 two or more recording instruments in order that several transcribing operators may be employed to divide the work and thus greatly facilitate and insure the handling of the traffic.

25 I accomplish the above noted desirable results by employing a novel relay system in effect interposed between the initial telegraph or cable receiving relay and a plurality of recording instruments whereby 30 groups of signals comprising complete messages are distributed between the several recording instruments to divide the work of transcription.

In the drawing which accompanies and 35 forms a part of this specification I have illustrated diagrammatically one complete embodiment of my idea as applied to cable telegraphy utilizing two direct writers or recording instruments.

40 Referring now to the drawing, cable 1 is shown with an earth connection 2 and with the initial receiving or cable relay 3 connected thereto as usual. Relay 3 is adapted to operate the local corrector relays 5 and 45 6 through the medium of battery 4. The forward or marking contacts of the relays 5 and 6 are connected to the windings of the regenerative relays 11 and 12. The windings are further connected through the common 50 return conductor 26 and through battery 9 with the tongues of both relays 5 and 6. The organization thus far described is the usual system of circuits and apparatus employed to receive, correct and regenerate 55 cable signals for recording purposes and is

deemed therefore to need no detailed description. My novel relay system is essentially interposed between the relay system just described and the recording apparatus as will now be pointed out. The relay 18 is 60 polarized and provided with tongues 19 and 20, carried on a common armature shaft 17 but insulated therefrom and from each other. Tongue 19 is associated through one of its contacts with one pole of battery 23, the 65 other pole of which is connected to a pole of opposite polarity of a similar battery 24 and through condenser 22 and bridged resistance 21 with one terminal of the winding of relay 18 and also through resistance 27 with 70 the other terminal of the winding of the relay. The midpoint of the relay winding is connected to the back contact of relay 5. The remaining terminal of battery 24 is connected to the other contact associated with 75 tongue 19, which is connected through retardation coil 10 with the back contact of relay 6. This system of circuits and apparatus constitutes the well known Gulstad method of relay operation and serves as a 80 means for vibrating the added tongue 20 between its associated contacts at all times when the circuit from the split battery 23—24 through tongue 19 is closed by the tongues 7 and 8 of relays 6 and 5 respectively. 85

One terminal of the moving coil of direct writer 14 is connected to the tongue of regenerative relay 11 and to one of the contacts associated with tongue 20 of relay 18. One terminal of the coil of direct writer 15 90 is similarly connected to the tongue of regenerative relay 12 and to the remaining contact associated with tongue 20. The remaining terminals of the coils of writers 14 and 15 are connected through conductor 16 with the tongue 20 of relay 18. This results in the direct writers being connected in series relation to operating impulses received through the contacts of relays 11 and 12 from battery 13 and as tongue 20 is moved to make contact alternately with its contacts, direct writers 14 and 15 will be alternately short circuited and rendered thereby inoperative. 95

100 The operation of my relay system is as follows:

105 Relay 18 is controlled by the incoming signals received by relay 3 and remains de-energized and with its tongue at rest on the contact with which it last made contact 110

so long as a continuous sequence or group of incoming signals is being received, because armatures 7 and 8 of relays 6 and 5 are during such time in constant motion, and the circuit through tongue 19 of relay 18 is therefore not closed for the predetermined period of time necessary to charge condenser 22 to cause the operation of relay 18. If however, the sending operator provides a pause of predetermined time duration between messages both armatures 7 and 8 will come to rest on their respective back contacts to close the circuit from split battery 23-24 through tongue 19 for a time interval equal to that provided by the sending operator and sufficient to charge condenser 22 to initiate the vibration of relay 18, and thus to alternately short circuit direct writers 14 and 15. This of course distributes a complete message to first one and then the other of the direct writers and so divides the work for the transcribing operators. The direct writers are operated preferably in series, with one or the other alternately short circuited, in order that a poor contact between tongue 20 and either of its contacts will not result in the loss of a message.

Condenser 22 is provided with a non-inductive shunt resistance 21 to prevent a gradual accumulation of charge which would in time be sufficient to reduce the effective capacity of the condenser and cause relay 18 to operate on transmitting pauses of less than the predetermined time interval provided for the purpose.

I have found that for cable telegraphy a pause equal to the time interval represented by the passage through the transmitter of the length of tape between six center holes, when provided between messages, operates my relay system very effectively in conjunction with a condenser of approximately 40 microfarads shunted with a 5,000 ohm non-inductive resistance, and a variable resistance of 300 ohms with which to refine the speed adjustment. Obviously the timing of the vibrations of relay 18 is determined by adjustment of resistance 27 and condenser 22 to attain the speed of operation required. The speed should be such that armature 20 moves from the contact upon which it is at rest while the relay is de-energized to the other contact in the time interval selected and interposed between messages. In other words in the time interval that the tongues 7 and 8 are at rest on their back contacts.

The inductance or retardation coil 10 is provided in the circuit of tongue 19 to retard the current to permit condenser 22 to discharge on isolated single letter words such as E or T.

While I have shown and described but one embodiment of my device it should be clearly understood that I may vary the details thereof widely without departing from the spirit or narrowing the scope of my invention.

Having thus completely disclosed and described my invention, I claim:

1. A signal receiving system comprising a plurality of receiving relays, a pair of ink writers, vibrating relay means, means for suppressing operation of said vibrating relay means only while signals are being received, said vibrating relay means determining which one of said ink writers shall record the received signal.

2. In a relay distributor, means for receiving telegraph signals, a pair of signal recording means and means operable by the cessation of said signals for a predetermined time interval for distributing said signals in groups to said recording means in alternation, both of said recording means being associated with said receiving means.

3. In a relay distributor, means for receiving signals, a first and second means for recording said signals and means operable only by the cessation of said signals for a predetermined period of time for determining whether said first or said second recording means shall record said signals, said first and second recording means being both associated with said receiving means.

4. In a relay distributor, means for receiving signals, a plurality of means for recording said signals and means operable only by the cessation of said signals for a predetermined period for determining which one of said plurality of signal recording means shall record said signals, all of said recording means being associated with said receiver.

5. In a relay distributor, means for receiving signals, a plurality of means for recording said signals, and means operable only by the cessation of said signals for a predetermined time interval for rendering first one and then another of said recording means inoperative, all of said recording means being associated with said receiver.

6. A signal receiving system comprising, a plurality of receiving relays, a pair of ink writers, vibrating relay means, means for suppressing operation of said vibrating relay means only while signals are being received, said vibrating relay means determining which of said ink writers shall record the received signal said vibrating relay means being connected to said ink writers in such manner as to prevent loss of signal record in event of failure of said vibrating relay contacts.

HENRY JOSEPH SINNOTT.
